JAMES H. COGSHALL, OF LEXINGTON, MICHIGAN.

Letters Patent No. 62,010, dated February 12, 1867.

IMPROVED NURSING-COUCH.

The Schedule referred to in these Letters Patent and making part of the same.

TO ALL WHOM IT MAY CONCERN:

Be it known that I, JAMES H. COGSHALL, of Lexington, in the county of Sanilac, and State of Michigan, have invented a new and useful Improvement in Nursing-Couch; and I do hereby declare that the following is a full, clear, and exact description thereof, which will enable others skilled in the art to make and use the same, reference being had to the accompanying drawings forming part of this specification, in which—

Figure 1 is a vertical longitudinal section of my improved couch, taken through the line $x x$, fig. 2.

Figure 2 is a vertical cross-section of the same, taken through the line $y y$, fig. 1.

Similar letters of reference indicate like parts.

My invention has for its object to assist the mother in nursing her child, by compelling her to sit upright, and at the same time giving that support to the muscles of the arm which she requires; and it consists of a couch upon which the child is laid, which is made adjustable in height by the vertical screw that pivots it to the support or standard, which is made adjustable in inclination by a semicircular arm and set-screw, as hereinafter more fully described.

A is the standard, consisting of the foot or horizontal part a^1 and the upright or vertical part a^2 . The upright part a^2 is perforated with a vertical hole, in which a screw-thread is cut for the reception of the screw B, as shown in fig. 1. C is the couch or table, the lower part of which is made semicircular in form, or has side flanges, and the whole upper part of which is upholstered, so as to form a secure and comfortable resting-place for the child, and at the same time a comfortable support for the mother's arm. B is the screw, by means of which the couch C is pivoted to the support A, and by means of which the height or elevation of the couch may be regulated at pleasure. The upper end of the screw B is pivoted to the under side of the couch C, as shown in fig. 2, which enables the inclination of the couch C to be varied, as the comfort or convenience of the mother or child may require. D is a semicircular arm, the ends of which are secured to the under side of the couch C, and which passes through and works in a hole or slot formed in the upper part of the screw B, as shown in figs. 1 and 2. The arm D is held in place, securing the couch or table C at any desired inclination, by the set-screw E, the point of which rests against the side of the arm D, clamping it securely to the screw B. F are straps, by means of which the child may be secured to the couch C, if desired. The support A, and screw B, may be made short, so that the apparatus may rest upon the mother's lap; or, if desired, they may be made longer, so as to rest upon the floor. Pivoting the couch C to the support A by the screw B, not only enables the elevation of the said couch C to be adjusted as required, but it also enables the mother to conveniently revolve the child from one breast to the other. The upper part or end of the couch C is designed to support the mother's arm while nursing the child, thereby relieving her from the consequent fatigue and weariness.

What I claim as new, and desire to secure by Letters Patent, is—

The nursing-couch, consisting of the support A, screw B, set-screw E, semicircular arms D, table C, and straps F, when constructed and arranged as herein set forth.

JAMES H. COGSHALL.
